UNITED STATES PATENT OFFICE.

DAVID E. SMITH, OF OSWAYO, PENNSYLVANIA.

OIL-CUP.

SPECIFICATION forming part of Letters Patent No. 659,159, dated October 2, 1900.

Application filed November 1, 1899. Serial No. 735,527. (No model.)

To all whom it may concern.

Be it known that I, DAVID E. SMITH, a citizen of the United States of America, residing at Oswayo, in the county of Potter and State of Pennsylvania, have invented a certain new and useful Improvement in Oil-Cups, of which the following is a specification.

My invention relates to an improvement in oil-cups, and more particularly to that class 10 which I term an "automatic ball-feed oiler," one object being, as the name implies, to provide a cup which is automatic in operation—that is to say, one in which the discharge of oil is automatically shut off when the motion 15 of the machinery to which the cup is applied ceases and which automatically opens when the machinery starts.

A further object is to provide means whereby the extent of movement of the ball-valve 20 is regulated and varied in accordance with the speed of the moving part to which my improved oil-cup is attached.

A still further object is to provide a cup which will be thoroughly economical in the 25 consumption of oil.

With the foregoing objects in view my invention consists in certain novel features of construction and combinations of parts, which will be hereinafter described, and particularly pointed out in the claims.

In the accompanying drawings, Figure 1 is a view in side elevation, and Fig. 2 is a vertical section.

A represents the body portion of the cup, it 35 being preferably made of glass, as is customary, so that the contents can be seen from the outside. This may be cylindrical, if desired, or in any other convenient shape, and at its lower end it is reduced, as at 1. At 40 this point it is embraced by the upturned flange 2 of the base-ring 3, a rubber gasket or other packing 4 being interposed between the glass cylinder and the base to make a tight joint at this point. This base portion has a 45 screw-threaded plug on its lower side adapted to screw into a hole for its reception over the bearing to be lubricated, and to the angular portion 5 a wrench or other tool is applied for screwing or unscrewing the oil-cup.

Projecting upwardly from the base and centrally located thereon is the threaded nip-

ple 6, and through the base-plug and nipple an oil-duct 7 is formed for the escape of the oil from the cup to the part to be oiled. A tube 8 is screwed onto the nipple 6 and extends some distance above the top of the cup, its upper end being screw-threaded, as at 9, and the portion within the cylinder having orifices 10 therein for the passage of oil from the cylinder thereinto. Screwed upon this 60 tube 8 and embracing the upper end of the cylinder is a cap 11, which holds the cylinder securely between it and the base-ring 3, a gasket or packing 12 preferably being interposed between said cap and cylinder. An 65 oiler 13 in this cap supplies the cylinder with oil when it is desired to refill it. A nut 14 is screwed upon the upper end of the tube, and a jam-nut 15 holds this nut 14 in its adjusted position upon the tube. The hole 16 is for 70 the passage of air through the nut 14. A valve-seat 17 is fitted in the lower end of the tube 8. This valve-seat is made of wood which is adapted to become saturated with oil, and wood is employed in preference to other 75 materials because it will not corrode. It has a duct 18, which opens into duct 7, and its entire upper surface is concave, as shown at 19. In this concaved upper surface a ball 20 is placed, the function of the latter being to insure an immediate closure of the duct 18 against the escape of oil when the machinery is at rest. The ball 20 may be made of glass or other suitable material, and its weight and size are sufficient to always insure a perfect automatic operation. Depending into the tube 80 centrally from the nut 14 is the spindle 21, its object being to regulate the size of the chamber in which the valve 20 moves, the nut being screwed on or off of the threads 9 85 on the upper end of tube 8 accordingly as the speed of the engine or machinery to which the cup is applied is fast or slow, the lower end of the spindle acting to regulate the size of this chamber, as the diameter of the ball- 90 valve 20 is greater than the space between the spindle and the tube 8, so that it is impossible for the ball to enter the said space, and its movements are altogether confined between the valve-seat and the end of the 100 spindle. Consequently the raising and lowering of the nut 14, which carries this spin-

dle, will necessarily regulate the capacity of the chamber in which the ball-valve 20 vibrates.

When in motion, the oscillations of the 5 part to which the oil-cup is connected cause a more or less rapid vibration of the ball in accordance with the speed of the machine, and its constant return to its seat has the effect of, in a measure, a force-feed upon the 10 oil at the orifice of the duct, thus keeping the part thoroughly lubricated, a constant supply of oil being fed into the tube 8 from the surrounding glass cylinder. The moment the machinery ceases to move the valve 15 gravitates to the orifice of the duct, where it seats itself and absolutely shuts off all further supply of oil, so that there is no waste when the machinery is at rest. Heretofore oil-cups have been provided with valves 20 which required closing by hand when the machinery stopped and which when forgotten, which was not an uncommon occurrence, wasted their entire complement of oil and not infrequently resulted in a hot-box when the 25 machinery was started without the engineer being conscious that the oil had wasted. This objection is entirely obviated in my invention by the provision of the automatic ball-feed, which absolutely insures a closure of 30 the oil-duct the moment the machinery ceases to move and as long as it is at rest and which, on the other hand, opens the duct automatically as well as soon as the machine begins to move.

35 It is evident that slight changes might be resorted to in the form and arrangement of the several parts described without departing from the spirit and scope of my inven-

tion, and hence I do not wish to limit myself to the exact construction herein set forth; 40 but,

Having thus described my invention, what I claim as new, and desire to secure by Letters Patent, is—

1. The combination with a base-ring, a cylinder, a tube projecting outside of said cylinder, a cap and a valve-seat having an oil-duct therein, of a ball-valve, a nut on the upper end of the tube adjustable thereon and provided with a spindle which depends into 45 the tube, the space from the spindle to the tube being less than the diameter of the ball-valve whereby to limit the movements of the ball-valve, which space is regulated by the adjustment of the nut up and down on the 50 tube.

2. The combination with a base-ring having an oil-duct therethrough and provided with a screw-threaded nipple, a perforated tube screwed on the nipple, a cylinder and a 60 cap, the cylinder being held between the cap and the base-ring, of a valve-seat having a duct which leads into the duct in the base-ring and provided with a concaved upper surface, a ball-valve resting in the concaved 65 seat and adapted to normally close the duct, a nut adapted to screw on the upper end of the tube, said nut having an air-vent and provided with a depending spindle located centrally in the tube, the nut being adjustable on the tube whereby the size of the valve-space is regulated.

DAVID E. SMITH.
